(57) CLAIM

The ornamental design for a shoe sole, as shown and described.

DESCRIPTION

FIG. 1 is a perspective view of a shoe sole showing my new design;

FIG. 2 illustrates a top view of the shoe sole of FIG. 1;
FIG. 3 illustrates a bottom view of the shoe of FIG. 1;
FIG. 4 illustrates a left side view of the shoe sole of FIG. 1;
FIG. 5 illustrates a right side view of the shoe sole of FIG. 1;

FIG. 6 illustrates a front view of the shoe sole of FIG. 1; and,
FIG. 7 illustrates a back view of the shoe sole of FIG. 1.
The portions of the bottom surface which is left unshaded in FIGS. 3, 6, and 7, are not part of the claimed design.
